TIME CONTROLLED CIRCUIT MAKER AND
BREAKER

Frank Marzo, Washington, D. C.

Application October 8, 1936, Serial No. 104,719

5 Claims. (Cl. 200—35)

This invention relates to improvements in electric circuit controlling devices and contemplates such a device constructed and arranged to first complete an electric circuit at a predetermined time and later to interrupt such circuit, also at a predetermined time.

It is the purpose of the present invention to provide mechanism for attaining the above mentioned ends of such construction as enable the average householder to purchase and use one or more, and to this end the device is constructed of simple mechanism that permits of its manufacture at a relatively low price.

The device of the present invention contemplates switch mechanism adapted to be operated through the medium of a spring device, both for the circuit maker and the circuit breaker and it is the object of the invention to employ a conventional clock mechanism having setting devices adapted to control the said spring device whereby the switch may be caused to function at predetermined intervals.

An object of the present invention is to provide a clock mechanism having a spring device independent of the conventional motor spring and setting means whereby the spring may partake of two separate unwinding motions resulting in first a closing of an electric circuit and then an interruption of said circuit, each motion being at predetermined intervals.

It is a further object of the invention to provide a single switch device having two separate motions each operated by a single spring device which is in turn controlled by a conventional gear train as associated with the usual clock motion. The invention contemplates an actuating spring having two separate expansion periods, each expansion motion serving to impart a motion to the switch, first, to complete the circuit and second to interrupt the circuit.

A further and important object of the invention resides in the extreme simplicity of the mechanism employed to carry out the functions hereinbefore noted coupled with the low cost of manufacture. Many devices of this nature have been provided for accomplishing the same purposes of applicant's invention, but their complicated structures and the cost of manufacture has made them prohibitive to the average householder and it was with this feature in mind that led to an effort to provide a simple and efficient device that could be employed to control many electrical devices, such as radios, electric signs, signal devices and household appliances. The device of the present invention, while extremely simple in design, is high-

ly efficient in operation, strong, durable and cheap to manufacture.

Other and important objects and advantages of the invention will be apparent during the course of the following description, reference being had to the accompanying drawings wherein like numerals are employed to designate like parts throughout.

Referring to the drawings,

Figure 1 is a face view of a clock having two setting devices as embodied in the invention,

Figure 2 is a rear view thereof,

Figure 3 is a front view with the clock casing cut away to illustrate the mechanism therein,

Figure 4 is a vertical sectional view through the actuating spring and associated elements, taken on line 4—4 of Figure 3,

Figure 5 is a plan view of the clock mechanism illustrating the actuating spring and associated elements, parts of the clock mechanism being omitted,

Figure 6 is an enlarged fragmentary view illustrating the actuating spring in its completely wound position, together with the associated switch device,

Figure 7 is a similar view illustrating the spring in its first unwinding position,

Figure 8 is a similar view but with the spring in its completely expanded position,

Figure 9 is a similar view illustrating the switch motion during the rewinding of the spring,

Figure 10 is an enlarged view, partly in section, of the switch head,

Figure 11 is a fragmentary end view of the spring, and

Figure 12 is a diagrammatic illustration of the circuit wiring.

Referring specifically to the drawings, the numeral 5 designates a casing, formed of metal, wood or other suitable material. The casing is provided with a removable back section 6. Clock mechanism designated as a whole by the numeral 7 is supported within the casing as is customary and actuates the usual time indicating hands 8 operating over the conventional dial 9 carried by the forward face of the clock. The time operating mechanism is of conventional structure and will not be described in detail with the exception of so much as may be necessary for a connection to the operating parts of the switch control. As shown in Figures 1, 2, 3 and 5, the clock is provided with two separate time setting means, that is, an "on" set 10 and an "off" set 11, see particularly Figure 1. A power attachment plug 12 is illustrated in Figure 2 and an appliance con-

nection receptacle 13 is illustrated in Figures 2 and 3.

The switch operating mechanism is designated as a whole by the numeral 14 and comprises an operating spring device embodying a relatively wide spiral spring 14' wound about a shaft 15 that is mounted for rotation in the frame portion of the clock. A winding key 16 serves to rotate the shaft in one direction for placing the 10 spring under tension. As clearly shown, one end of the spring is connected to the shaft 15 while the opposite or outer end is attached to a barrel 17 as indicated at 18. It will be seen by reference to Figures 4 and 5 that the spring has a 15 width substantially twice the depth of the barrel. The barrel carries gear teeth 19 that mesh with the teeth of a relatively small gear 20 carried by a shaft 21. The shaft 21 carries an escapement wheel 22 engaged by an escapement dog 23 for 20 controlling the rotation of the shaft and incidently the barrel. A latch spring 24 normally prevents rotation of a shaft 25 through the medium of a finger engagement 26. The shaft 25 carries the dog 23. The "on" set device comprises a shaft 27 on which is slidably mounted a gear 28 having a cam device associated therewith. The end of the shaft 27 carries a pin that normally rides upon the upper surface of the cam. The gear 28 is turned through the medium of 30 the conventional time mechanism which will not be described in detail, other than to say that when the gear 28 is rotated to a predetermined degree, the cam will ride outwardly over the pin under the action of the latch 24, releasing the 35 finger 26 and permitting the shaft 21 to be rotated under action of the spring controlled barrel 17, the speed of rotation being retarded by the escapement devices 22 and 23. When the spring has expanded approximately one-half, a stop pin 40 29 (see Figures 6 to 9 inclusive) will have been projected under action of the spring 14' and when the barrel has rotated to the proper point, the pin 29 will engage a finger 30, also carried by the shaft 25. This action will lock the escapement 45 mechanism against movement and further movement of the barrel and its associated mechanism hereinbefore described will be prevented.

The structure so far described relates to the first movement of the actuating spring 14' and it should be here stated that during this initial movement the shaft 15 is held against rotary movement. Freely rotatable upon the shaft 15 and lying next to the spring 14' is a second gear 31, similar in size to the gear 19. The gear 31 55 carries a pivoted ratchet dog 32 upon its outer face for engagement with a winding ratchet 33 that is fixed to the shaft 15. The gear 31 engages and drives a small gear 20' upon a shaft 21'. The shaft 21' also carries an escapement wheel 60 22' engaged by an escapement dog 23' on a shaft 25'. A spring latch device 24' engages and normally holds a finger 26' against movement. The latch is normally held in engaged position by a sliding gear 34 that is carried by a shaft 35 designated the "off" control. This gear carries a cam face that rides upon a pin carried by the shaft 35 and upon a predetermined time will ride over the pin and be bodily moved endwise by the spring latch 24', whereby the finger 26' is released, permitting of a rotation of the shaft 21' 70 under the action of the spring 14' operating through the shaft 15, ratchet wheel 33, ratchet 32 and gear 31. The release of the gear 31 will permit the complete unwinding of the spring 14'. 75 It will therefore be seen from the foregoing that

the mechanism described will cause the spring to partake of two separate unwinding actions.

It will be understood that the shafts 27 and 35 are extended at their outer ends and carry the usual indicating hands, while their rear ends 5 are extended and carry hand set knobs.

The switch device comprises a flat bar 36 having perforated ends that are slidably positioned over guide pins 37. The pins 37 are carried by fixed bracket members 38 carried by the clock 10 casing. Compression springs 39 are carried by the pins 37 and engage upon the upper surface of the bar 36, normally urging it toward the brackets 38. Adjusting nuts are threaded upon the pins 37 for varying the degree of tension 15 upon the bar 36. As clearly shown in Figures 4 and 5, the bar 36 overlies the exposed portion of the spring 14' and when the parts are in starting position, the bar lies substantially upon the outermost coil of the spring 14', which is the normal position. The bar carries a centrally disposed upstanding arm 40 having a head 41, preferably formed of insulating material and having a metallic contact element passing therethrough as shown at 42. The head is adapted to pass between metallic contact elements 43 and 44 carried by a common bracket 45 of insulating material. A circuit is made between the head 41 and contacts 43 and 44 by a rubbing contact. Contact element 44 is hingedly mounted as at 46 upon the bracket 45 and is held against pivoting in the upward direction by an extension 47, but is freely movable downward against the action of a retractile spring 48. The ends of the contact elements are preferably surrounded by insulating material, as shown and for a purpose to be described.

The bar is caused to move upwardly under the action of the expansion of the spring 14', causing the head 41 to pass between the contacts 43 and 44 thus establishing an electrical connection. This initial positioning of the bar 36 is the first expansive motion of the spring 14' and the amount of expansion is so timed that when the head 41 lies between the contacts 43 and 44 the 45 spring 14' will be locked against further action until the "off" setting functions to permit a further and complete expansion. When the "off" setting operates to release the spring for a complete expansion, the bar 36 will move further 50 upward against the tension of the springs 39, such movement causing the head to pass beyond the contacts 43 and 44, thus interrupting the circuit.

When the mechanism is to be reset, the spring 14' is rewound through the medium of the key 55 16. As the spring 14' is rewound, the bar 36 moves downward under the action of the springs 39. It is important and desirable that during the downward movement of the head 41 past the contacts 43 and 44 that a circuit connection be not established, and to avoid this undesirable feature, the head is provided with a compressible latch element 49 pivoted at 50 and normally urged outwardly by a leaf spring 51. When the head is moving upwardly, the latch will be compressed, but when the head moves downwardly, the latch will engage the upper insulated portion of the contact 44 causing it to swing upon its pivot until the head and latch has passed out 70 of the arc thereof, at which time the contact will move upwardly into normal position under action of its spring. Thus it will be seen that in the downward movement of the head 41, the swinging of the contact 44 downwardly will pre- 75

vent an electrical contact between the several parts.

In order to prevent a bumpy motion between the bar 36 and spring 14' during the initial unwinding due to the reach of the spring end from its wound position to its connection with the barrel, the spring is cut away as indicated at 14'', see particularly Figure 11. Thus the actual contact between the bar and spring 14' will be a relatively smooth one.

The stop pin 29 is normally urged inwardly against the action of the spring 14' by a coil spring 28' engaging a head 29'' carried by the pin, thus when the parts are to be reset, a release of the spring 14' will cause the pin 29 to also move to normal position.

The operation of the device is as follows:

The parts being in their normal position, it being assumed that the spring 14' has been wound completely and the "on" and "off" controls have been set at predetermined intervals, as the time approaches where the gear 28 is rotated to the point where the cam snaps over the pin, the shaft 21 will be permitted to rotate due to a release of the latch 24, shaft 25 and escapement mechanism 22 and 23. This release will permit the gear 19 to rotate under the influence of the expansive force of the spring 14' and this expansion of the spring moves the bar 36 upwardly against the tension of the springs 39 until such time as the head 41 lies between the contacts 43 and 44. At this moment the pin 29 has been moved outwardly by the spring 14' a sufficient distance to engage the finger 30, such action preventing further movement of the shaft 25 and thereby locking the escapement device, shaft 21, gear 20 and gear 19 against further movement. When this operation has been completed, the spring 14' has been unwound approximately one-half. The unwinding of the spring has caused the gear 19 to move in the direction of the arrow. A circuit has now been completed from the source of power, through the contacts 43 and 44, head 41 to the receptacle 13, through the appliance to be controlled and back to the opposite pole of the source of current.

When the time approaches for an interruption of the circuit, the gear 34 has rotated to release its latch with the corresponding release of the escapement mechanism 22' and 23', shaft 21', gear 20' and large gear 31, at which time the spring 14' is permitted to complete its unwinding action, with the result that the head 41 is moved still further upward until it has passed beyond the contacts 43 and 44, this action serving to interrupt the circuit. The second unwinding action serves to rotate the shaft 15 in the direction of its arrow and this motion is imparted to the gear 31 through the medium of the ratchet dog 32 and ratchet wheel 33. It should be here stated that during the first unwinding action, the shaft 15 and gear 31 is held against turning movement. The mechanism is entirely set in its normal operative position by simply rewinding the spring 14' through the medium of the key 16, this action permitting the bar 36 to move downwardly under the influence of its springs 39 and the locking pin 29 withdrawn under action of its spring. The gears 19 and 31 are automatically locked against turning as the gears 28 and 34 are moved by the time mechanism of the clock, to cause the spring latches to engage the fingers 26 and 26'.

If found desirable, a condenser may be placed in the circuit to avoid sparking during the mak-

ing of the electrical contact. This however forms no part of the present invention.

It will be seen from the foregoing that an extremely simple and efficient form of circuit maker and breaker has been provided. The structure is such as may be very cheaply manufactured, combining in its makeup the time elements of the conventional moderate priced clock. While the invention is illustrated as combined with a clock employing a spring motor drive, it is obvious that it might just as readily be adapted to the well known electric clocks.

Further mention should be made relative to the rotary engagement of the spring 14' with the bar 36. The spring 14' as has been previously stated, is cut away as at 14'' for a distance equal to the distance between the point of connection with the barrel 17 and the outermost convolution in the completely wound condition. This will enable the bar 36 to lie against the outermost convolution when the spring is completely wound and will cause the bar to rise evenly as the spring unwinds, without jerky or uneven movements. If the spring was not cut away as indicated, the bar could not lie closer than the outermost end of the spring where it connects with the barrel 17.

It is to be understood that the invention is not limited to the precise construction shown, but that it includes within its purview whatever changes fairly come within either the terms or the spirit of the appended claims.

Having described my invention, what I claim is:—

1. The combination with a clock mechanism and a circuit controller, a spring motor having an expansible spring, the said motor controlled by the clock mechanism at predetermined intervals, said circuit controller lying in the path of expansive movement of the spring, a partial expansion of the spring serving to close the circuit, while a further expansion of the spring serves to interrupt the circuit.

2. The combination with a clock mechanism and a circuit controller, a spring motor associated with the clock and controllable by the clock for permitting intermittent movement thereof, said motor comprising an expansible spring adapted to partake of a plurality of separate expansive movements, said circuit controller lying in the path of expansive movement of the spring, the several independent movements of the spring serving first to complete an electric circuit and then to interrupt said circuit, the several motions controlled at predetermined intervals by the clock mechanism.

3. The combination with a time controlling mechanism and a circuit controller, a rotary spring motor associated with and controlled by the time mechanism, the said motor comprising a rotary housing and an expansible spring, means for permitting a partial rotation of the motor and a consequent partial expansion of the spring, means for permitting a further expansion of the spring, the said circuit controller lying in the path of expansive movement of the spring whereby the several motions of the spring will be imparted to the said circuit controller.

4. In combination, a clock mechanism and an electric circuit controller, a rotary spring motor associated with the clock and intermittently controlled thereby, the said motor comprising a rotary barrel and an expansion spring, means controllable by the clock for permitting a partial

- rotation of the motor with a consequent partial expansion of the spring, means operable by the expansive movement of the spring for positively limiting the initial rotative movement of the motor, means controllable by the clock for permitting a further expansion of the spring, the said circuit controller lying in the path of expansive movement of the spring, whereby the several expansive movements of the spring will be imparted to the controller for effecting first a closing of the circuit and second an interrupting of the circuit, the several movements of the motor being controlled at predetermined intervals by the clock mechanism.
5. In combination, a clock mechanism and a circuit controller, a rotatable spring motor embodying an expansible spring, said motor comprising a barrel, means controlled by the clock

for permitting a partial rotation of the barrel and a consequent initial expansion of the spring, means operable by the expansion of the spring for locking the barrel against further rotation, means operable by the clock for permitting a further expansion of the spring independently of the barrel, said circuit controller arranged in the path of expansive movement of the spring, the initial expansive movement of the spring serving to move the controller to a position for completing the circuit, a further expansive movement of the spring serving to move the controller to a position for interrupting the circuit, the several movements of the motor controllable at predetermined intervals by the clock mechanism and means for causing the several parts to move to their normal initial position.

FRANK MARZO.
